UNITED STATES PATENT OFFICE.

GEORGE C. SNYDER, OF NEW YORK, N. Y.

FASTENING DEVICE.

1,205,044.

Specification of Letters Patent.

Patented Nov. 14, 1916.

Application filed September 17, 1913. Serial No. 790,236.

To all whom it may concern:

Be it known that I, GEORGE C. SNYDER, a citizen of the United States, residing in the city of New York, county of New York, State of New York, have invented certain new and useful Improvements in Fastening Devices; and I do hereby declare the following to be a full, clear, and exact description of the invention, such as will enable others skilled in the art to which it appertains, to make and use the same.

The invention relates to a simple and efficient fastening device in the form of a one-piece hollow stud or eyelet, which may be used alone or in conjunction with other fastening devices or elements, and which is adapted to be firmly secured to sheet fabrics and textiles of all kinds, from the thinnest and sheerest gauze to the heaviest leather or textiles, without danger of tearing out or injuring the fabric.

To this end, the invention comprises, primarily, a hollow stud or eyelet made from a single piece of sheet metal having the body thereof formed with an outer shell, preferably with a peripheral basal flange, and an inner tubular shell turned inward and spaced from the outer shell and preferably extended in an axial direction beyond the basal flange on the outer shell, the extended portion of the inner shell being adapted to form an outwardly turned flange coöperating with the flange on the outer shell to clamp the material, to which the stud or eyelet is applied, between the flanges, after the fabric has been pierced or perforated and the edges surrounding the perforation forced inward into the space between the inner and outer shells where an additional clamping action on the fabric may be produced by compressing or constricting the inner and outer shells with respect to each other.

A further object of the invention is to provide a fastening device comprising a hollow stud or eyelet of the character indicated, associated with a head member which may be either integral therewith or attached thereto to constitute a button coöperating with a standard button hole, or in the alternative, to constitute one or both members of a separable fastening such as commonly employed in fastening gloves, curtains, garments and the like.

Various applications of the invention are

illustrated in the accompanying drawings, in which,

Figure 1 is a vertical section through a hollow stud or eyelet illustrating the mode of preliminarily applying the fabric thereto. Fig. 2 is a similar view showing the mode of forcing the fabric into the space between the inner and outer shells of the stud or eyelet. Fig. 3 is a corresponding view showing the formation of the flange on the inner tubular shell, thereby securing the fastening device to the fabric. Fig. 4 is a vertical section through a hollow stud or eyelet associated with a separate button head and the means for attaching the head to the stud or eyelet. Fig. 5 is a plan view of the device shown in Fig. 4. Fig. 6 is a modification showing a one-piece button made in accordance with the invention. Fig. 7 is a section through a separable fastener of the glove type involving a stud member and a socket member, each made in accordance with the invention, the two members being shown as initially applied to the fabric flaps. Fig. 8 is a corresponding view showing the separable fastening, as illustrated in Fig. 7, attached to the respective flaps. Fig. 9 is a fragmentary sectional detail showing a modified form of the coöperating flanges on the outer and inner shells of the stud member.

Referring to Figs. 1, 2 and 3 of the drawings, a hollow stud or eyelet member is formed of a single piece of material, preferably thin sheet metal capable of being pressed, spun or otherwise shaped, comprising an outer shell 1 having an outwardly extending basal flange 2 about its lower edge, the upper edge of the shell 1 being turned or spun over to form an integral part or continuation of the tubular axially aligned inner shell 3, the lower portion of which inner shell is extended beyond the plane of the basal flange 2 on the outer shell as indicated in Figs. 1 and 2. The hollow studs or eyelets having the form and physical characteristics just described may be manufactured by any machinery suitable for the purpose, and are designed to be sold to the users with the lower portion of the inner shell extending in alignment with the main body portion of said inner shell, as indicated. Obviously, the hollow stud or eyelet, as described, may be made of any suitable material, but will preferably be constructed

from single pieces of non-corrosive sheet metal capable of being stamped, drawn, punched or otherwise worked into the desired shape.

- 5   In applying a stud or eyelet member of the character described to the fabric or other goods to which it is to be secured, the stud or eyelet is first threaded upon a sharp pointed punch, such as α , shown in Fig. 1, and the fabric pressed down over the punch and the extended end of the inner shell, the punch merely perforating the fabric without rupturing the threads or fibers thereof, if the fabric is of a textile nature, and
- 10   merely stretching and parting the fibers or body constituents of the material when the latter is leather or other similar material. The tool α is then removed and a tubular mandrel, such as y in Fig. 2, is applied to
- 15   force the material surrounding the projected end of the inner shell 3 into the annular space between the inner and outer shells, thereby causing the material to be snubbed in a circular or annular bite about the rim or edge formed by the junction of the basal flange 2 with the outer shell 1. The tubular mandrel y is then withdrawn and an upsetting die punch preferably of the form shown at z in Fig. 3 is passed
- 20   through the open center of the stud or eyelet and the latter is forced downward against the rounded anvil or shoulder of the punch, by any appropriate means, thereby causing the projected end of the inner shell
- 25   to be turned outwardly to form a flange 4, substantially parallel with the flange 2 and securely clamping the fabric α between the flanges 2 and 4, the maximum clamping effect being produced between the interior angle formed at the junction of flange 4 with the inner shell and the exterior angle formed by the junction of the flange 2 of the exterior shell. It will be observed that the fabric is not only compressed between the flanges 2 and 4, but is strongly compressed and gripped in the angles between the flanges and the inner and outer shells respectively, and if desired, a still further clamping effect may be produced by compressing or constricting the annular space between the inner and outer shells above the flanges thereon, which may be accomplished by making the spindle of the die punch z above the anvil tapering so as to spread or
- 30   expand the inner shell, as shown in Fig. 3. It will also be noted that the fabric is clamped in an annular zone sufficiently remote from the rim or edge of the hole in the fabric made by the punch α to prevent
- 35   the fabric raveling or tearing loose when strain is put upon the fabric.

The particular exemplification of the invention illustrated in Figs. 4 and 5 involves the same type of hollow stud or eyelet formed of a single piece of sheet mate-

rial, as that illustrated in Figs. 1 to 3 inclusive, and applied to the fabric in the same manner and to the same effect. In addition to the hollow stud or eyelet however, the fastening device is provided with 70 a button head 7, which may be of metal, bone, rubber, celluloid, or other suitable composition or material, having a tubular neck 8, which surrounds the outer wall 1 of the hollow stud or eyelet. The latter is applied to the fabric as hereinbefore indicated. The button head is slipped over the stud or eyelet and subjected to the action of a spreading punch w , which enters the hollow of the stud or eyelet and expands the 75 upper portion thereof laterally to cause the upper edge of the outer wall to curl over in a rounded flange or bead 5 to engage the annular opening in the head 7 while the inner wall 2 is pressed outwardly as at 6, 80 thereby not only affording a rigid clamping action between the hollow stud or eyelet and the head 7, but also serving to more effectively finish the rivet like joint between the hollow stud or eyelet and the button 85 head. It will be noted that the bead-like flange 5 on the stud or eyelet affords a neat, smooth joint between the stud or eyelet and the button head, and thereby eliminates the rough, unsightly and objectionable features 90 of the old types of buttons which were secured by the ordinary forms of hollow rivets or studs, and obviates the necessity of an extra cap piece.

In Fig. 6 there is illustrated a modification of the invention, in which the button head 7' is formed as an integral part of the inner and outer shells 1 and 3 respectively, the outer shell 1 being extended outwardly to form the bottom wall of the button head 100 and the inner shell 3 being similarly extended to form the upper wall of the button head 7'. This embodiment of the invention constitutes a one-piece button which may be applied to its intended use in the same manner and to the same effect as the hollow stud or eyelet exemplified in the first three figures, or the two-piece button shown in Figs. 4 and 5, in each case the junction between the fastening and the fabric being 105 effected by the secure and rigid clamping action produced by the coaction of the shells 1 and 3 and the flanges 2 and 4.

In Figs. 7 and 8, the invention is shown as applied to separable fasteners of the 110 glove type, in which both the stud and socket members of the fastener are formed of a single piece of sheet metal in accordance with the invention. As illustrated, the stud member comprises an outer shell 1' having 115 a tubular neck terminating in a basal flange 2', the outer portion of the shell having a bulbous or globular form. The inner shell 3' is formed with a similar concentric bulbous or globular body portion terminating 120

in a tubular neck portion projecting beyond the flange 2' so that an annular space is left between the inner and outer shells. The socket member which is made sufficiently 5 large to receive the stud member is formed in substantially the same manner, comprising the bulbous outer shell 1" with the basal flange 2'', and the bulbous inner shell 3'', terminating in the tubular or cylindrical 10 neck. Both the stud and the socket members are preferably kerfed or slotted diametrically to render the respective members sufficiently springy or resilient to permit the stud to be forced into locking engagement 15 with the socket. Preferably, the kerf 8' in the stud member is disposed at right angles to the corresponding kerf 8'' in the socket member. The two unitary members of the 20 separable fasteners are attached to the respective flaps of the gloves, garments, or other articles to which they are to be applied, in the same manner as the other forms of the invention, namely, by threading the 25 flaps of the fabric over the projected tubular ends of the inner walls of the respective fastener members and then turning down the flanges 4' and 4'' on the stud and socket members respectively, into clamping engagement 30 with the fabric, as illustrated in Fig. 8. Fig. 9 exemplifies a modification of the 35 clamping action between the flanges on the inner and outer shells of the stud member, the flange 2'a on the outer shell 1 being bent first horizontally and then vertically, while the flange 4'a on the inner shell 3 is made somewhat narrower and is adapted to be bent horizontally to lie in the angle between the horizontal and vertical portions of the

flange 2'a, thereby securing a double snubbing or gripping action between the corresponding edges or angles of the flanges and the fabric and also causing the flange 4'a to lie below the surface of the fabric or substantially countersunk in the fabric to prevent the metal part of the fastening device coming in contact with the body of the wearer or with other adjacent fabrics. 40

What I claim is:—

1. A fastening device for fabrics comprising a hollow stud or eyelet formed of a 50 single piece and involving an outer tubular shell and an inner co-axial tubular shell, said shells being substantially parallel and defining an annular space between them, a portion of the fabric being inserted between 55 said shells and the inner shell being expanded to clamp the fabric in said annular space between the shells, substantially as described.

2. A fastening device for fabrics comprising 60 an outer shell, a co-axial tubular inner shell spaced from the outer shell to form an annular space in which a portion of the fabric is inserted, and coöperating flanges on the outer and inner shells to grip the fabric inserted 65 between the shells, the walls of the inner shell being spread into close proximity with the walls of the outer shell to clamp the fabric in said annular space.

In testimony whereof I affix my signature, 70 in presence of two witnesses.

GEORGE C. SNYDER.
